SCAFFOLD

Samuel Zeno, McKeesport, Pa.

Application March 2, 1945, Serial No. 580,531

8 Claims. (Cl. 304—11)

My invention relates to scaffolds and particularly to those made in the form of portable units that can conveniently be transported from place to place.

One object of my invention is to provide scaffold units that can readily be applied to standard forms of ladders and which can conveniently be raised and lowered to desired height without the necessity of removing the walkways or scaffolding boards.

Another object of my invention is to provide scaffold apparatus that can readily be assembled and disassembled for packing and transportation.

In the accompanying drawings, Figure 1 is a side elevational view of the apparatus; Fig. 2 is an enlarged plan view of the spreader or spacer element of Fig. 1; Fig. 3 is an enlarged sectional plan view through the structure of Fig. 1 showing the staging portion of the apparatus in plan, and Fig. 4 is a view showing certain of the elements of the structure of Fig. 1, and taken on the line IV—IV.

The apparatus can be employed in connection with ladders of various standard forms, having the usual stiles 6 and rungs 7. A spacer or spreader device is removably connected to an upper portion of the ladder and comprises a cross bar 8 that may be of springy wood or spring metal and having secured thereto a pair of gripper arms 9 that are braced by struts 10, the outer ends of the members 9—10 being riveted or bolted together at 11. In order to apply the spreader to the ladder, the arms are sprung apart as indicated by the dash lines in Fig. 2, the cross bar 8 flexing for this purpose, as indicated by the dash lines. The bar 8 will abut against the side of the building with which the scaffold is to be used, and the spreader will be retained in place by frictional force resulting from the resilience of the bar 8.

The apparatus includes a bracket structure having a pair of horizontal bars 12 which are, however, here shown as made of a tube that is flattened intermediate its end and at its extremities and suitably bent as shown in Fig. 3. These members could, of course, be made of flat bars, if desired. The bar 12 is flattened and bent at its mid portion 13 to partially embrace a strut member 14 that, at its lower end, is connected with a tubular cross bar 15 that carries spool-like rollers 16 which make anti-frictional engagement with the ladder stiles 6.

A rod 21 extends through the outer ends of the arms 12 and carries a pipe 22 that bears against the outer edges of the stiles and functions as a

roller for anti-frictional engagement with the stiles. A tube 23 is welded at its ends to the bracket arms 12. A flap board 25 is tightly supported on the pipe 22 by straps 26, and when swung to its full line position of Fig. 1, will extend beneath the tube 23 so that when it is resting on a ladder rung, at points between the pipes 22 and 23, the bracket will be firmly supported.

A tie rod 30 is connected at its lower end to the tube 15 as shown more clearly in Fig. 4 and at its upper end is connected to the tube 23. A looped member 31 is also connected to the tube 18 and to a pull rope 32 that extends upwardly and around a pulley 33 that is connected to an upper rung of the ladder. The rope is of such length that it will extend to the ground at a point outside the scaffolding. The flap board 25 is cut away at its inner edge as shown in Fig. 3, to accommodate rod 30.

Two ladders each containing the bracket structure are provided to support the ends of scaffolding boards or a walkway 34, each bracket being manipulated by its rope to raise and lower that end of the walkway. In order to raise the scaffold boards at each end, the outer end of the rope 32 is pulled. This causes the pipe 22 to roll upwardly along the stiles and thereby rock the flap board 24 toward its dash line position of Fig. 1. When the desired height has been reached, a slight lowering will cause the tube 26 to rotate clockwise and swing the lower edge of the flap board into position above the next lower rung so that it can come to rest in its full line horizontal position. Because of the suspension of the board by the straps 26, it will tend to tilt to a position at which its inner or lower edge will swing over a ladder rung. Weight on its outer edge will likewise cause it to function somewhat as a pawl to engage the rungs independently of the rolling action of the tube 22.

In order to lower the bracket, the rope will be pulled sufficiently high to lift the flap board clear of the rung, whereupon movement of the rope 32 to its dotted line position of Fig. 1 will hold the board in approximately a vertical position, and while rope is held close to the ladder, the bracket and the staging can be lowered.

I claim as my invention:

1. A scaffold device for use with ladders, comprising a bracket adapted to support a walking plank, means slidably supporting the bracket on ladder stiles, for movement longitudinally thereof, a device carried by the bracket, for releasably engaging ladder rungs and maintaining the bracket at desired vertical points on the stiles,

a rope connected to the bracket and adapted to be looped over a guide at the top of the ladder, so that a pull on the free end of the rope will raise the bracket along the stiles, the said device being arranged to swing downwardly relative to the bracket when it is being elevated, and to swing into supporting position over a rung when it has been raised past the same, the said device being pivotally supported intermediate its edges, and its outer edge being engageable by the rope, whereby it may be tilted out of engagement with the ladder rungs when the free end of the rope is moved toward the ladder.

2. A scaffold device for use with ladders, comprising a bracket adapted to support a walking plank, means slidably supporting the bracket on ladder stiles, for movement longitudinally thereof, a bracket-supporting device comprising a member pivoted thereon at the outer side of the ladder and with its inner end normally extending beneath an upper portion of the bracket at the inner side of the ladder and arranged to automatically move into overlying relation on a ladder rung, at a point between its said inner end and the pivoted point, and means for raising and lowering the bracket and for swinging and holding the said member out of rung-engaging position, the last-named means comprising a rope connected to the bracket and adapted to be looped over a guide at the top of the ladder.

3. A scaffold device for use with ladders, comprising a bracket adapted to support a walking plank, means slidably supporting the bracket on ladder stiles, for movement longitudinally thereof, a bracket-supporting device comprising a member pivoted thereon with its inner end extending beneath the bracket and arranged to automatically move into overlying relation on a ladder rung, at a point between its said inner end and the pivoted point, and means for raising and lowering the bracket, the said member being pivoted intermediate its end, and a rope connected to the bracket and adapted to be looped over a guide at the top of the ladder, whereby it may be used to raise and lower the bracket, and the outer strand of the loop be moved against the outer edge of the pivoted member to hold it tilted out of rung-engaging position, when lowering the stage.

4. A scaffold device for use with ladders, comprising a bracket adapted to support a walking plank, means slidably supporting the bracket on ladder stiles, for movement longitudinally thereof, a bracket-supporting device comprising a member pivoted thereon with its inner end extending beneath the bracket, means carried by

the bracket and rotatably engaging the ladder stiles, for rocking the said member toward and from horizontal position during raising and lowering movements of the bracket.

5. Scaffold structure comprising a ladder, a spreader having arms frictionally gripping upper portions of the ladder stiles in position to extend horizontally against a vertical wall and adjustable longitudinally of the stiles, a bracket slidably engaging the stiles of the ladder and extending from the ladder toward the wall, means operable from the ground, to raise the bracket on the stiles, and means for automatically locking the bracket at its raised positions.

10 15 6. A scaffold device for use with ladders, comprising a bracket adapted to support a walking plank, means slidably supporting the bracket on ladder stiles, for movement longitudinally thereof, a bracket-supporting device comprising a board pivotally connected to the bracket at the outer side of the ladder and with its inner end movable into position above a ladder rung and beneath a portion of the bracket at the inner side of the ladder, means for raising and lowering 20 25 the bracket, and means for simultaneously swinging the board into and out of overlying relationship with a ladder rung.

7. A scaffold device for use with ladders, comprising a bracket adapted to support a walking plank, means slidably supporting the bracket on ladder stiles, for movement longitudinally thereof, a bracket-supporting device comprising a roller rotatably carried by the bracket in position to engage the outer edges of the stiles for rotative movement thereon during raising and lowering movements of the bracket, together with a holding member connected to the roller and tiltable through rotative movements of the roller into and out of overlying relation to ladder rungs, and means for releasably retaining said holding member in inoperative position during the lowering movements of the bracket.

30 35 40 45 50 55 8. A scaffold structure comprising a ladder, a spreader having arms frictionally engaging the ladder stiles and extending transversely thereof in position to seat against a wall at their free ends, means on the spreader arms for holding the stiles against movement in directions longitudinally of the arms, the spreader being slidably adjustable longitudinally of the stiles, a bracket slidably engaging the stiles of the ladder and extending from the ladder toward the wall, in a plane below the spreader, and means shifting the bracket longitudinally of the stiles.

SAMUEL ZENO.
